Harry M. Young.
BY Ralph Reich
ATTORNEY

UNITED STATES PATENT OFFICE.

HARRY M. YOUNG, OF ST. LOUIS, MISSOURI, ASSIGNOR TO WESTERN WIRE PRODUCTS COMPANY, OF ST. LOUIS, MISSOURI, A CORPORATION OF MISSOURI.

SPRING MATTRESS.

Application filed December 14, 1923. Serial No. 680,639.

To all whom it may concern:

Be it known that I, HARRY M. YOUNG, a citizen of the United States, residing at the city of St. Louis, State of Missouri, have invented a certain new and useful Improvement in Spring Mattresses, of which the following is a specification, reference being had to the accompanying drawing, forming a part thereof.

10 This invention relates to a certain new and useful improvement in spring-mattresses of the type that includes a link, woven, or knitted wire-fabric or other so-called yielding or resilient body and has for its chief 15 object the provision of a spring-mattress of the type stated comprising a supporting-frame or structure so constructed that the yielding properties or resiliency—the stretch or tightness of the woven, link, or knitted 20 fabric or other resilient or yielding body of the mattress may be conveniently adjusted or regulated to increase or decrease the tension or stiffness of the body to meet different individual requirements.

25 With the above and other objects in view, my present invention resides in the novel features of form, construction, arrangement, and combination of parts hereinafter described and pointed out in the claims.

30 In the accompanying drawing,

Figure 1 is a broken plan view of a spring-mattress embodying my invention;

Figure 2 is a side elevational view of the mattress; and

35 Figures 3 and 4 are, respectively, perspective and front elevational views of one of the body-adjusting brackets of the frame of the mattress.

40 Referring now more in detail and by reference characters to the drawing, which illustrates a preferred embodiment of my invention, A designates the so-called yielding or resilient body of the mattress, which is in the form preferably of any suitable woven or knitted wire fabric.

45 Supporting the body A, is a frame comprising head-rails 1, 1', preferably of angle-iron form, to which heads 1, 1', the body A is suitably attached at its longitudinal ends preferably through the employment of a plurality of coil-springs or the like 2, as best seen in Figures 1 and 2 and as will be well understood, the lateral margins of the body A being preferably bounded or finished

55 by suitable so-called "sag-rails" 3, 3, similarly attached at their ends to the frame-heads 1, 1'.

50 Riveted or otherwise rigidly fixed to, and depending from, the opposite ends of frame-head 1, are preferably rigid corner-brackets 4, 4, of any suitable or standard form and construction; and riveted or otherwise rigidly fixed to, and depending from, the opposite ends of the other frame-head 1', are the upper members 5, 5, of corner-brackets B of novel form and construction, now to be described.

55 The member 5 of each bracket B is substantially in the form of an angle and comprises a main wall flat at its upper portion, as 70 at 6, to fit smoothly against and for riveted engagement with the inner face of the depending limb of the head-rail 1', and preferably bodily curved or arcuated, as at 7, from its flat portion 6 to its lower end, as 75 shown. Integral with said wall at its opposite side edges, are lateral strengthening flanges 8, 8', the flange 8' extending upwardly slightly above the upper margin of flat wall-portion 6 and said wall and its flange 8' being provided with a ledge 9 having its upper face disposed in the plane of the upper margin of the wall-portion 6 and its other flange 8, so that the bracket-member 5 may snugly seat in riveted or fixed 80 position upon the end margin of the head-rail 1', as shown. Projecting rearwardly from the lower margin of and approximately at right angles to said main wall, is a so-called plate or bottom wall 10 preferably 85 rounded at its free edge; and formed upon the bracket-member 5 and projecting forwardly from, and at the lower margin of, its said main wall, is a pair of suitably spaced pivot-lugs or ears 11, 11. Integral 90 with said main and bottom walls, is preferably a plate-strengthening web 12, best seen in Figure 3.

95 Co-operating with its member 5 and forming the complementing part of the bracket B, is an oppositely disposed angle member 13 comprising a main wall 14 formed upon its one side and lower margins with a substantially continuous lateral strengthening flange 15 and upon its other side margin with a lateral strengthening flange 16, the flanges 15 and 16 at the inner lower corner of the member 13 merging into a rearwardly 100 105

presented socket 17 also, in turn, integral at its closed end with the wall 14. Projecting rearwardly from the upper margin of and approximately at right angles to side wall 14, is a second so-called plate or upper wall 18 similarly rounded at its free edge and in opposing companionship to the bottom wall 10 of the bracket member 5; and projecting forwardly from and at the upper margin of said wall 14, is likewise a pair of suitably located pivot-lugs or ears 19, 19. Disposed lengthwise through and having engagement with the pairs of ears or lugs 11, 11, and 19, 19, for pivotally or hingedly securing or fastening the angle-members 5 and 13 together, is a pintle 20.

Seated for threaded movement in the bottom-wall 10 of bracket-member 5 and engaging at its lower end upon the opposing upper wall 18 of the bracket-member 13, is a bracket-adjusting screw or the like 21.

Completing the body supporting structure or frame and seated at one end in the sockets 17 of the brackets B and at the other end in companion-sockets 22 of the brackets 4, are frame side-bars 23.

In use, as will be well understood, the complete mattress is suitably disposed upon a bed-frame, not shown, and normally, as illustrated in Figure 2, the adjusting-screw 21 is in such seated or adjusted condition as to somewhat arcuately or hingedly space the wall-members 10 and 18 of the bracket B, when, as will be obvious, the body A will be stretched or distended to a certain degree of tension or stiffness. Should, however, it be desired to increase the stiffness or tension and thereby further reduce the resiliency or yielding condition of the body A, then the screw 21 may be so further manipulated as to correspondingly further hingedly space the bracket-walls 10 and 18, such movement of the bracket-member 5 shifting the head-rail 1' away from the fixed head-rail 1 and consequently stretching the fabric body A and its fastening springs 2 and thereby tightening or increasing the tension of the same upon the supporting structure. Conversely, should it be desired to reduce the stiffness and increase the resiliency or yielding properties of the body A, then the screw 21 may be so reversely manipulated as to correspondingly permit the bracket-wall 10 to hingedly move toward the bracket-wall 18, such latter movement of the bracket-member 5 shifting the head-rail 1' toward the fixed head-rail 1 and reducing the pull or tension upon the body A and its fastening springs 2 and thereby loosening the same upon the supporting structure.

My new spring mattress is simple, compact, and relatively inexpensive in form and construction, is convenient, positive, and durable in adjustment, readily accommodates the requirements for comfort of dif-

ferent individuals and thereby enables the manufacturer to increase his production with a standardization of product, permits ready adjustment of either longitudinal side of the mattress independently of the other, and is exceedingly efficient in the performance of its intended functions.

I am aware that changes in the form, construction, arrangement, and combination of the several parts of my new spring-mattress may be made and substituted for those herein shown and described without departing from the nature and principle of my invention.

Having thus described my invention, what I claim and desire to secure by Letters Patent is:

1. A spring-mattress body-adjusting bracket comprising a first casting including a main wall for engagement with the head rail of the mattress, a bottom wall projecting rearwardly from, and approximately at right angles to, the lower margin of said main wall, and pintle-ears projecting forwardly from and also at the lower margin of said main wall, a second casting also including a main wall for engagement with a side rail of the mattress, an upper wall projecting rearwardly from, and approximately at right angles to, the upper margin of said second main wall, and pintle-ears projecting forwardly from and at the upper margin of said second main wall, a pintle having engagement with the ears of said castings for hingedly securing the same together with said upper and lower walls in opposed relation, and a screw-member seated in one of said opposing walls and adapted for engagement with the other opposing wall for hingedly shifting the castings relatively to each other.

2. A spring-mattress body-adjusting bracket comprising a first casting including a main wall flanged at its upper end for engagement with the head rail of the mattress, a bottom wall projecting rearwardly from, and approximately at right angles to the lower margin of said main wall, and pintle ears projecting forwardly from and also at the lower margin of said main wall, a second casting also including a main wall, a socket upon said second main wall for engagement with a side rail of the mattress, an upper wall projecting rearwardly from, and approximately at right angles to, the upper margin of said second main wall, and pintle ears projecting forwardly from and at the upper margin of said second main wall, a pintle having engagement with the ears of the first and second castings for hingedly securing the castings together with said upper and lower walls in opposed relation, and a screw member adjustably seated in one of said opposing walls and adapted for engagement

with the other opposing wall for hingedly shifting the castings relatively to each other.

3. A spring-mattress body-adjusting bracket comprising a first casting including a main wall flanged at its upper end for engagement with the head rail of the mattress, a bottom wall projecting rearwardly from, and approximately at right angles to, the lower margin of said main wall, pintle ears projecting forwardly from and also at the lower margin of said main wall, and lateral strengthening flanges at the opposite side margins of the main wall, a second casting also including a main wall, a socket upon said main wall for engagement with a side rail of the mattress, an upper wall projecting rearwardly from, and approximately at right angles to, the upper

margin of said second main wall, pintle ears projecting forwardly from and at the upper margin of said second main wall, and lateral strengthening flanges upon the lower and side margins of the second main wall, some of which merge into the wall of said socket, a pintle having engagement with the ears of the first and second castings for hingedly securing the castings together with said upper and lower walls in opposed relation, and a screw member adjustably seated in one of said opposing walls and adapted for engagement with the other opposing wall for hingedly shifting the castings relatively to each other.

In testimony whereof, I have signed my name to this specification.

HARRY M. YOUNG.
